DOOR FASTENER

William Patterson, Merion, Pa.

Application October 7, 1948, Serial No. 53,343

1. Claim. (Cl. 292—292)

1

My invention relates to new and useful door fasteners and particularly devices which may be employed as temporary fasteners or in connection with a mechanically controlled means to actually function as locking instrumentalities.

An object of the invention is to provide a strong, light portable fastener which may be employed to lock a door from either the outside or the inside, the drawers of desks, household furniture and the like, drop lids of storage bins or boxes, other swinging or sliding items and similar apparatus.

Another object of the invention is to provide a device of this character which is simple in construction although strong and durable and which can be employed to lock a door, and many other items, even when the door structure does not have a lock or latch keeper.

Usually devices of a somewhat similar character when employed to fasten a door in closed position must be located on the inside of a compartment and generally require that a keeper or lock-bolt or latch receiving aperture be present or provided in the door frame. My fastener does not require such accessories and can be easily applied without appreciable defacement to the door frame and can be utilized to lock a door from the outside, for example, a closet door, which closet may contain clothing, jewelry or other valuable articles. Therefore, it will be apparent that not only can the door to a room be locked from the inside but such a door may be locked securely from the outside, especially a closet door, by the use of an individual padlock and key, which will keep out prowlers or curious persons.

A further object of this invention is to provide, in combination, an arm to be attached to a door frame or the like and a sleeve to be slipped over said arm and having a laterally projecting stop plate to engage a swinging or sliding item, such as a door, said arm and sleeve provided with aligning apertures to receive a securing means, such as the bow of a padlock.

With the above and other objects in view this invention consists of the details of construction and combination of elements hereinafter set forth and then designated by the claim.

In order that those skilled in the art to which this invention appertains may understand how to make and use the same I will describe its construction in detail, referring by numerals to the accompanying drawing forming a part hereof, in which:

Figs. 1 and 2 are isometric views of two similar arms of different lengths.

2

Fig. 3 is a perspective view of the sleeve or slide.

Figs. 4-5 are fragmentary perspective views of door jambs with fasteners thereon illustrating different mounting arrangements.

Fig. 6 is a similar view showing molding on the door frame and the manner in which a longer arm should be mounted thereon.

Fig. 7 is a fragmentary perspective view, on a reduced scale, of portions of a plain frame and door showing the completely assembled fastener in holding position.

Fig. 8 is a further reduced face view of the arm on a door frame.

15 Fig. 9 is an end view of the arm and sleeve mounted for holding a door in closed position, and

Fig. 10 is a perspective view of a slightly modified form of fastener adapted to hold a pair of doors in closed relation.

20 In carrying out the invention as herein embodied, reference being first had to Figs. 1 to 9, inclusive, 15 represents the holding arm comprised of a flat piece of sheet metal having one or more holes 16 in the inner end through which

25 are projected fastening devices 17, such as screws, for attaching said arm to a supporting element 18, such as a door frame, and a single aperture 19 in the outer end to receive the bow 20 of a padlock 21, Fig. 7, or other securing or holding device. The holding arm 15 may be of different lengths for mounting on door frames having different types of finishing molding, and on a face of said holding arm is a series of spaced indication marks 22 and associated indicia 23. The indication marks start at a shoulder 24 on one edge of said arm and extend rearwardly any suitable or preselected distance.

30 A fastening member 25 includes a rectangular shaped tubular sleeve 26 having a sliding fit on the holding arm 15 and provided at its inner end with a laterally projecting wing plate 27 to engage or contact a face of a door 28 or equivalent movable element, such as drawers in articles of furniture. In the outer end of the sleeve is formed an aperture 29 to receive the bow 20 of the padlock 21 or other securing or holding device whenever said aperture 29 aligns with the aperture 19 in the outer end of the holding arm. It is to be understood that the aperture 29 passes through both of the opposed side walls of the sleeve.

35 40 45 50 When the door fastener is to be installed, the style of the door frame or jamb and the condition of the door, whether it fits flush or is sprung or warped, must be taken into consideration. If the door fits its frame or jamb in practically

55

perfect or flush condition the holding arm is set back until the shoulder 24 is substantially even with the adjacent corner or outer face of said frame, as shown in Fig. 4, but if the door is sprung, warped or is thicker than the depth of the door receiving recess, the indication marks are utilized to properly install the holding arm of the device. This is accomplished by merely judging or determining the distance the outer face of the door projects beyond the outer face of the adjacent portion of the frame while the door is closed. Then it is decided which one of the indication marks 22 is a distance back of the shoulder equal to the predetermined distance between the outer faces of the door and its frame and the holding arm is installed with the proper indication mark in alignment with the plane of the outer face of said frame. This will cause the holding arm to project the necessary distance to permit the holes 19 and 29 to be aligned, Fig. 1, or locate the fastening member 25 beyond the hole 19, Fig. 2, when said fastening member is placed on the holding arm 15 and moved into engagement with the shoulder 24. Should the type or style of the door frame be such that a protuberance, for example, a molding 30, Fig. 6, extends beyond the outer face of the main frame or normal position of the outer face of a closed door, a long holding arm is used. In every instance the holding arm 15 is mounted on the inside edge of the door frame or jamb so that there will be practically no defacement of said door frame when the arm is removed as only three or less screw holes will remain and even these will not be visible when the door is closed.

In practice, when the door is closed against its jamb, with a holding arm in fixed position and protruding beyond the face of the door opposite the jamb, a fastening member 25 is slipped over the holding arm in a manner to cause the wing plate to be disposed in the path of travel of the door towards its open position. At such a time the sleeve portion of the fastening member 25 will be in engagement with the shoulder on the holding arm. Under a condition where a short arm 15 is employed, the engagement of the sleeve with the shoulder will cause an alignment of the apertures 19 and 29 so that the bow of a padlock, a staple or even a nail may be inserted to hold the parts in place and prevent opening of the door with a pass key or if not locked by any usual locking means. Where it is necessary to employ a long holding arm, the fastening member 25 may be projected over said arm until the sleeve engages the shoulder which will expose the aperture, or said holding member may be positioned to cause the apertures 19 and 29 to align with one another. In the first instance the bow of the padlock is placed in the aperture 19 only to prevent the fastening member being withdrawn whereas in the second instance the bow of the padlock is inserted in both apertures for the same purpose although it might be possible to open the door slightly.

As illustrated in Fig. 10, the door fastener may be applied to double swinging or sliding doors in which case the holding arm 15 is secured to the meeting edge of one door 31 and a hasp 32 is secured to a face of the other door 33. To lock the two doors, a fastening member 25a including the sleeve portion 26a with the aperture 28a therethrough and the lateral wing plate 27a which, in this case, has an elongated aperture 34 to fit the hasp 32. After the bow of a padlock has been inserted in the hasp 32, the two doors cannot be slid apart nor swung in either direction because of the binding action between the sleeve portion of the fastening member and the holding arm due to the straight line formation of said sleeve and arm and the arcs in which the doors swing.

It is to be fully understood that when the device is manufactured the elongated aperture 34 may be formed in the wing plate although not actually utilized thus providing a fastener adapted for use in either of the ways illustrated in the drawing.

From the foregoing it will be apparent that the present device may be carried in a person's pocket, hand bag or luggage for use wherever desired and can be employed to securely lock a door. Whether or not the latter is provided with a lock or even a lock keeper and provides means for locking a door with a person's individual or private lock key.

Of course I do not wish to be limited to the exact details of construction herein shown and described as these may be varied within the scope of the appended claim without departing from the spirit of my invention.

Having described my invention what I claim as new and useful is:

In a device of the kind described, a holding arm secured to the inner edge of one of a pair of co-acting doors and projecting beyond a face of the door to which said arm is secured, a hasp secured to a face of the other door on the same side as the projecting end of the holding arm, a sleeve slidable over the projecting end of said holding arm, and an integral wing plate extending laterally from the inner end of the sleeve and provided with an aperture to permit said wing plate to pass over the hasp after which a padlock may be applied to said hasp for locking the two doors together.

WILLIAM PATTERSON.
